STRETCHING APPARATUS FOR SCREEN CLOTH

Gustave A. Overstrom and George Overstrom,
Eagle Rock, and Conrad Overstrom, Altadena,
Calif.

Application April 13, 1940, Serial No. 329,446

5 Claims. (Cl. 209—403)

This invention relates to improvements in stretching apparatus for screen cloth of the type illustrated by the patent to Gustave A. Overstrom, No. 2,136,950, issued November 15, 1938.

The main object of the invention is to provide a screen stretching bar and a liner bar therefor in which the liner bar is held in place independently of the stretching bar.

A further object of the invention is to provide stretching apparatus for a screen cloth in which the stretcher means is free to slide into engagement with the cloth to stretch said cloth independently of and without regard to the position of the liner bar.

A further object of the invention is to provide means, independent of each other, for holding a liner bar and a stretcher bar in slidable contact.

A further object of the invention is to provide a liner bar that is easily removable from the machine without detachment from a stretching bar.

A further object of the invention is to provide spring means for holding the liner bar down firmly on top of and in frictional contact with the screen cloth when it is being stretched.

Heretofore, when apparatus of this character was used, the stretcher bar would slide into engagement with the cloth, and the liner bar, being attached thereto, of necessity would have to be adjustable. It was found in practical operation that when the liner bar was bolted to the stretcher bar, operators would not unloosen the liner bar from the stretcher bar when additional stretching of the cloth was required; and as a result the liner bar acted as an effective stop and would not permit the stretcher bar to freely move into engagement with the cloth to effect further stretching. This was particularly found true when the stretching apparatus was used in screen structures employed to screen rotary drill mud. This mud often carries an acid in it that corrodes the threads of bolts and nuts, making it difficult for the operator to loosen the same so that free movement of the stretcher bar could be had, and as a consequence they frequently met difficulty in using a liner bar structure such as is illustrated by Patent No. 2,136,950.

In the construction as illustrated in Patent No. 2,136,950, the liner bar is attached to the stretcher bar by means of bolts embedded in and carried by the stretcher bar, and the liner bar is bolted to the stretcher bar after the stretcher bar had effected its operation of stretching the cloth. This invention entirely does away with the bolts and attachments carried by the

stretcher bar to effect fastening of the liner bar thereto.

This invention resides substantially in the combination, construction, arrangement and relative location of parts, all in accordance with 5 this disclosure.

Referring to the accompanying drawing and to the various views and reference signs appearing thereon:

Figure 1 is a plan view of a screening apparatus with parts broken away, showing the liner bar and the stretcher bar of this invention; 10

Figure 2 is an elevation of Figure 1 with parts broken away, showing the stretcher bar;

Figure 3 is an enlarged cross-sectional view of 15 Figure 2, taken along the line 3—3 of Figure 2, looking in the direction of the arrow with some parts broken away; and

Figure 4 is an enlarged side elevation of the liner bar with a portion broken away. 20

In the drawing the same part is designated by the same reference sign.

Referring now to the drawing in detail, there is illustrated somewhat diagrammatically a screen structure illustrating the manner of application of this invention thereto. The structure is illustrated as comprising a support consisting of a pair of side frames 1 made of any suitable material, such as metal. The ends 2' of the coil springs 2 are bolted to the tops of the side frame members 1. There are four of these springs longitudinally spaced in pairs to provide a support for the screen box 4. This screen box is provided with brackets 3', secured thereto in any suitable manner, having pintles 3 attached to the inner ends of the coil springs 2. Thus the screen box is supported at its four corners. 25

The screen box is made up of side channels, as is clear from the figures, which are interconnected by cross-braces 8, 9 and 10 of any suitable shape; all of these parts being made of iron or steel and preferably welded together into a rigid structure. Extending longitudinally of the cross-braces and resting or attached thereon are the rails or bars 11 and 12. The bars 11 are positioned close to the side frame channels in parallel relation therewith but spaced therefrom, as is clear from Figure 3. There are two or more of the rails 12, depending upon the width of the screen box. Secured to the side frame channels 30 are the brackets 7 in which is secured a tubular housing 6 within which are sealed bearings in which an unbalanced shaft 5 is journaled for rotation. This shaft is provided with a pulley 5' by means of which it may be rotated from any 35

suitable external source of power. The rotation of the shaft 5 in the direction of the arrow, as indicated in Figure 2, effects vibration of the screen box in a closed curved path which lies substantially in a vertical plane.

In the screen box and forming the floor thereof is the screen cloth 4' which rests on the bars 11 and 12, which are preferably slightly curved longitudinally, as indicated in Figure 2. The bars 10 12 have secured on the tops thereof resilient supports 12' for the screen cloth 4' in accordance with well known practice in the art.

The screen cloth is stretched transversely of the screen box by means of stretching mechanism of the general type disclosed in the above-mentioned patent but in accordance with this invention modified as will now be described. A pair of stretcher bars 13 having longitudinally curved lower edges lie along the inner faces of 20 the side frame channels of the screen box 4 and are engaged along their top edges by means of vertically adjustable bolts 13'. The space between the side frame channels and the bars 11 is such that when the stretcher bars move down 25 between them, with the side edges of the screen cloth 4' extending around the lower edges of the stretcher bars, a friction fit will result. Thus as the stretcher bars are moved downwardly the screen cloth 4' is drawn tight transversely.

30 Lying along the inner faces of the stretcher bars 13 are the liner bars 14 which are likewise longitudinally curved along their lower edges so as to mate with the longitudinal curve of the bars 11. The liner bars 14 are supported by a 35 plurality of spring strips 15 which are riveted to them by the rivets 16 which engage plate washers 17 nested into the liner bars so as to be flush with the outer faces thereof. The upper ends of the spring supports 15 overlie the top flanges of the side frame channels. Clamping plates 15' engage these upper overlying ends of the springs 15 and are bolted to the side frame channels by the nuts and bolts 18.

By means of this construction it will be seen 45 that the stretcher bars 13 move up and down independently of the liner bars 14 which are spring-pressed against the stretcher bars and are positioned vertically so as to rest under spring tension on the top adjacent surfaces of the screen cloth. These liner bars serve to prevent un- 50 screened material from running down on the cloth over the rail 11, as well as preventing abrading material from lodging between the cloth and rail 11 and stretcher bar 13.

55 The screen cloth is originally inserted, or an old cloth is replaced by a new one, by substantially the following procedure: The stretcher bars 13 and the liner bars 14 are removed from the screen box. The cloth to be inserted is laid out flat on a suitable surface. It comes, of course, somewhat wider than the distance between the inside faces of the side frame members 4 of the screen box. The longer side edges of the screen are bent at right angles out of the plane of the 60 cloth so that the space between the flanges thus formed is equal to the distance between the inside faces of the sides 4 of the screen box. The width of the flanges thus formed is the same along both edges and throughout their length. The cloth 65 will, of course, maintain this shape because as commonly used in the art it is of metal, being woven of wire strands of suitable size.

The screen cloth is then inserted in the machine with its flanges extending upwardly. The 70 stretcher bars 13 are then placed in the machine 75

so that the upturned flanges of the cloth lie between the stretcher bars and the channel faces, as will be clear from Figure 3. The screws 13' are then tightened down and since they engage the top edges of the stretcher bars 13 they force 5 these bars down into the space between the channels 4 and the rails 11. The cloth is thus caused to take the shape clearly shown in Figure 3, and as the stretcher bars move downwardly they cause the cloth to stretch transversely and 10 become taut. The liner bars 14 are then put in place. At any time the tension in the screen cloth can be changed by properly adjusting the screws 13.

It will be seen from the above that the features 15 of the screen cloth stretching mechanism of the patent above-mentioned are retained in this mechanism while the cloth stretching parts are protected.

While a preferred embodiment of the invention 20 has been disclosed and described herein, it is to be understood that those skilled in the art will appreciate many changes and modifications which can be made without departing from the spirit and novel scope of the invention herein 25 disclosed. We do not, therefore, desire to be limited by the foregoing description, but rather by the scope of the claims granted us.

What we claim is:

1. In a vibrating screen structure, a screen 30 box having side members, longitudinal supports in said screen box extending parallel to but spaced from the side members, a screen cloth for the screen box and resting on said longitudinal supports, stretcher bars engaging the side edges of 35 the screen cloth to frictionally clamp them between the side members and the longitudinal supports, and spring supported liner bars pressed against the sides of said stretcher bars and on top of the adjacent areas of the screen cloth. 40

2. In a vibrating screen structure, a screen box having side members, longitudinal supports in said screen box extending parallel to but spaced from the side members, a screen cloth in the screen box and resting on said longitudinal 45 supports, vertically movable stretcher bars engaging the side edges of the screen cloth frictionally between the frame members and the longitudinal supports, and resiliently supported liner bars held in contact with the sides of said stretcher bars, so that the stretcher bars may be adjusted vertically independently of the liner bars. 50

3. In a vibrating screen structure, a screen box having side members, longitudinal supports in said screen box extending parallel to but spaced 55 from the side members, a screen cloth resting on said longitudinal supports, vertically movable stretcher bars engaging the side edges of the screen cloth frictionally between the frame members and the longitudinal supports, liner bars 60 lying against the inner faces of the stretcher bars, and supports for attaching the liner bars to the side members whereby the stretcher bars may be moved independently thereof.

4. In a vibrating screen structure, a screen box 65 having side members, longitudinal supports in said screen box extending parallel to but spaced from the side members, a screen cloth resting on said longitudinal supports, vertically movable 70 stretcher bars engaging the side edges of the screen cloth frictionally between the frame members and the longitudinal supports, liner bars lying against the inner faces of the stretcher bars, and spring supports secured to the liner bars and to the side members for holding the 75

liner bars tightly against the stretcher bars and in contact with the adjacent areas of the screen cloth.

5. In a vibrating screen structure, a screen box, a screen cloth in said box, vertically adjustable stretcher bars for engaging the side edges of the screen cloth to draw it tight in a transverse di-

rection, and resiliently supported liner bars frictionally engaging the stretcher bars while permitting independent movement thereof.
